LEONARD GRASSO,

By
Franklin D. Dugay Attorney

UNITED STATES PATENT OFFICE.

LEONARD GRASSO, OF WASHINGTON, DISTRICT OF COLUMBIA.

CATAPULT FOR GAME BOARDS.

1,403,402.

Specification of Letters Patent. Patented Jan. 10, 1922.

Application filed February 17, 1921. Serial No. 445,753.

To all whom it may concern:

Be it known that I, LEONARD GRASSO, a subject of Italy, residing at Washington, in the District of Columbia, have invented certain new and useful Improvements in Catapults for Game Boards, of which the following is a specification, reference being had therein to the accompanying drawings.

This invention relates to game boards and has for an object to provide an improved board with instrumentalities whereon and wherewith a game may be played analogizing a game of baseball.

A further object of the invention is to provide a game board having one or more catapults with improved means for adjusting the stress exerted and with features carried by the board for co-acting with the projectile actuated by the catapult.

20 A further object of the invention is to provide a game board having one or more catapults wherein the projecting force is an elastic band replaceable to vary the stress of the force, and with adjusting means for varying the movement or throw of the catapult actuated by the elastic band.

25 A further object of the invention is to provide a board having improved means for temporarily registering the various points of the game, making it convenient to eliminate such record as the progress of the game may make necessary or desirable.

30 A further object of the invention is to provide a game board having pockets for the detention of the projectile, such pockets being in the form of wickets arranged upon planes at an angle to each other, or V-shaped.

35 With these and other objects in view the device comprises certain novel units, elements, parts, features, and combinations as will be hereinafter more fully described and claimed.

In the drawings:

Figure 1 is a top plan view of the improved game board;

Figure 2 is a view of the game board in side elevation;

Figure 3 is a fragmentary perspective view of one corner of the game board showing the catapult arrangement on an enlarged scale;

Figure 4 is an enlarged sectional view taken on line 4—4 of Figure 1;

Figure 5 is an enlarged perspective fragmentary view of a part of the board showing the obstructions and wickets;

Figure 6 is a detail perspective view of the hammer part of the catapult;

Figure 7 is a detail view of one of the wickets;

Figure 8 is a detail view of a modification of the wickets made in two sections, and

Figure 9 is a detail fragmentary view of a slight modification in the tension arrangement for the catapult, but sufficiently analogous to be represented by line 9—9 of Figure 1.

Like characters of reference indicate corresponding parts throughout the several views.

While the game board disclosed in the present application is, as above stated, intended for the playing of a game analogous to baseball, the invention itself resides in the board and not in the game played thereon. The board comprises a substantially plane base member 10 having a rail 11 about the margin and set for playing at an inclination, as indicated at Figures 2 and 4, such inclination being maintained in any approved manner, as by a leg 12. At the end which would be the upper end when so elevated, curves 13 are produced, such curves meeting at a downwardly extended point 14 centrally of the board. Along the sides and adjacent to the side rails 11, catapults are arranged for the purpose of initiating the movement of a projectile through the passages 15,—such a projectile being shown at 16,—into engagement with the curves 13 provided sufficient force is employed for so projecting the projectile.

For initiating the movement of the projectile, a hammer 17 is mounted to slide in the passage 15 and is actuated by the employment of an elastic band 18. Preferably, means for adjusting the tension of the band relative to the hammer is provided, one of such means being by employing a staple 19 inserted in openings 20 in the hammer 17, a sufficient number of said openings being provided, as indicated at Figure 6, to permit the adjustment of the staple 19 longitudinally of the hammer 17. The staple 19 is inserted through one of the loops of the elastic band 18, the opposite end being held by a hook 21 which may be made adjustable by providing a plurality of perforations 22 into which is inserted the extremity 23.

To prevent the withdrawal of the hammer 17 from the passage 15 a pin 24 is pro-

vided spanning such passage, and a plurality of openings 25 for such pin may be provided, as indicated at Figure 3, which will further provide adjustment for the catapult. This adjustment provided by the pin 24 in the openings 25 will limit the backward movement of the hammer against the tension of the band 18. It is obvious that the tension thus exerted will have an influence upon the initial velocity of the projectile and that, instead of relying upon the stop provided by the pin, manual variations may be accomplished so that the players may, by manipulating the catapult, project the projectile at varying initial velocities, thereby varying the result.

The board 10 is provided with a plurality of obstructions which are represented by the pins 26 set in any approved manner in the field. The pins 26 are useful only in preventing movement of the projectile along a straight line. A plurality of pockets 27 are of such dimensions and construction as to receive and retain the projectile 16. The pockets are preferably in the form of wickets and may be of double formation, as indicated at 28 in Figures 5 and 7, or may be two wickets associated, as indicated at 29, in Figure 8, the result being identical in either case.

At any convenient place on the board, as, for instance, adjacent the lower edge, a strip 30 is provided having a plurality of openings 31 in which characters are positioned by means of stems 32, as indicated more particularly at Figure 4. These characters preferably indicate men, as indicated at 33 in Figure 4 and are employed in the playing of the game in the manner which will suggest itself.

Also at some convenient place, as between the strip 30 and the lower edge of the board, a strip 34 is employed for the receipt of records of the play as it progresses. This strip is preferably of some material upon which record can readily be made and as readily eliminated. For instance, the strip 34 may be slate and the marks produced thereon by a slate pencil in the usual and ordinary manner. Certain divisions will be marked upon

such strip for the receipt of data indicating the points of the play as it progresses, in the usual manner. While the strip 34 has been shown as of different material from and, therefore, not integral with the surrounding physical features, it is obvious that this is merely a matter of choice and that the record tablet 34 may be of any material separated from or integral with the contiguous parts. At the locations indicated upon the board as "Home," "First Base," "Second Base" and "Third Base" a plurality of openings 35 are provided corresponding to the openings 31, so that the men 33 removed from the openings 31 may be positioned in the openings 35 as the play requires.

As the exact game to be played on the board forms no part of the present invention and as the operation of the device depends upon the game played, no description of the operation will make the board per se any more understandable than the foregoing description, and further description is, therefore omitted.

What I claim to be new is:

1. A catapult for a game board embodying a passageway comprising a hammer slideable in the passage, said hammer being provided with a plurality of spaced sockets, 80 an elastic band, means to attach the elastic band to the board, and means engaging the elastic band and engageable in any of the sockets selectively.

2. A catapult for a game board embodying a passage in parallelism with an inclined side comprising a hammer slideable in the passage and provided with a plurality of spaced sockets, an elastic band, a hook for engaging said elastic band at one end, 90 and a staple engaging the elastic band at the opposite end and adjustable in said several sockets.

In testimony whereof I hereunto affix my signature in presence of two witnesses.

LEONARD GRASSO.
